(54) **HORSE POWER, OR ANIMAL**

(76) Inventor: **William E. Arnold**

William C. Arnold of Chatham, State of Connecticut.

The Schedule referred to in these Letters Patent and making part of the same containing a description in the words of the said William C. Arnold himself, of his improvement in the machine for applying Horses, or other animal power, to sundry mechanical purposes . . . .

To all to whom these presents shall come, Be it known that I, William C. Arnold, of Chatham in the County of Middlesex and State of Connecticut, have invented a new and useful improvement in a machine for the application of Horses or other animal power to sundry mechanical purposes, and that the following is a full and exact description of the construction and operation of said machine as invented or improved by me.

This machine is eleven feet and two inches long, ten feet wide and nine inches deep, the sides and ends of which are made of two inch plank, framed or dovetailed together. Thirteen pieces of board three quarters of an inch thick and four inches wide, crop from one side plank to the other, and are dovetailed into them on the under side at equal distances and from another. On the top of these boards and near the side planks, are two strips of board, three inches wide and three quarters of an inch thick, and running the whole length of the machine. In the central part of the machine, two feet by three inches from each end thereof, and three and a half inches from the upper edge of the sides, are ten pieces of boards, six inches wide and one inch thick which go from one side plank to the other and rest in them. On the top of these boards and against the inside of the planks are two bars of iron six feet and two inches long, two and a half inches wide and three eighths of an inch thick. Two feet and two inches from the forward end of the machine, and three and a half inches from the upper edge of the side planks, is a shaft, two inches square, made either of wrought or cast iron, which turns in cast iron boxes, composed of two parts, and set in the side planks. The shaft extends eight inches out from the sides of the machine for

the purpose of applying to it drums or gearing). On the shaft within the side planks are two cast iron spur wheels, four inches in diameter and one and a quarter inches thick. At the hinder end of the machine, three inches from the end, and three and a half inches from the upper edge of the side planks, are two other wheels or rollers running on bolts or arbors secured firmly in the planks. These are nine wooden treads for the horse to travel on, each two feet long, fourteen inches wide and one inch and a half thick, and sheathed or covered on the top with good substantial plank, one and a half, or two inches thick. Through both ends of each tread is a round iron or axis, one inch in diameter; the axis, at the end of each tread nearest the forward end of the machine, is seventeen inches long and extends from the sides of the tread an inch and a half inch, and the other axis is twenty inches long, extending from the sides of the treads three inches. On each end of this round iron or axis, is a friction roller for the treads to run on. An iron chain, or a rope or belt goes from the spur wheels at the forward end of the machine to the wheels or rollers on the hinder end on each side of the machine. The chains are made with square links so as to mesh over the spur or cogs on the wheels. The chains, ropes, or belts, are also attached to the ends of the longer iron or axes which pass through the treads. There is a piece of timber fourteen inches long and two inches square pinned on each end of the side planks, three inches from the top, and nine inches from the forward end of the machine, on the inside of the planks which reach within one and a half inches of the spur wheels. On each of these pieces, are two pieces of iron, one of which is eight and the other twelve and a half inches long, and one inch square. The shorter piece is worked or bevelled off to a wedge at both ends on opposite sides and holes are made one inch from one end and screws or bolts go through them into the timber, four feet long and two inches square above mentioned ten inches from the forward end of them, & the other end drops down

on the lower part of the machine towards the forward end for the friction rollers of the shorter axis of the treads to run upon. The pieces of iron twelve and a half inches long, are fastened at one end near the ends of the others, and fall the other way on pins fixed in the sides of the machine to prevent their going too low. At the hinder end of the machine four inches from the ends of the iron bars and seven inches from the end of the machine are two pieces of timber, pinned to the side planks, three and three quarters inches from the top thereof, fourteen inches long and two inches square. On the top of each of the side planks is a board, an inch thick, placed even with the planks on the outside & extending over them two or three inches on the inside and made fast by screws. The forward ends of these boards are directly over the shaft before described. Of the same length and thickness with these boards, and eight inches in width are two other boards over the rollers, fastened near the lower edge, by screws or nails to the inner edge of the former, and bevelled or rounded off, so as to bring the upper edges even with the outside of the side planks. On the outside of the side planks of the machine is a frame consisting of four posts or uprights two inches square fastened to the side planks, by pins or screws at the ends of the boards last mentioned and rising two feet and a half above the top of the side planks. These uprights on each side are made steady & firm, by braces extending from the upper end of one to the other at the upper edge of the side planks, crooking and falling into each other at the point of crooking. At the upper end of these uprights on the outside towards the ends of the machine are two pieces of timber two inches square, extending across from one upright to the other, fastened at one end by a bolt or screw so as to move, and resting at the other end in a wooden or iron catch or notch. The ends of the machine on the outside of the frame are covered with two or three planks of convenient thickness, but the centre of the end of each tread, which is towards the forward end of the machine, may be

firmly fixed a piece of iron a quarter of an inch thick and an inch and a half wide and extending one inch out of the head and so fitted as to enter a place or mortise in the end of the head following it as it rises in the forward part of the machine, for the purpose of giving steadiness to the motion of the treads and of preventing their moving sideways. The pieces of timber near the two ends of the machine and the four pieces of iron in the forward end may be omitted altogether and the two axes at the ends of each head be made of the same length as the shorter, but in such case the wheels or rollers in the hinder end of the machine must be placed about half the length of one tread farther from the end of the machine and the spur wheels in the other end about as much nearer to the forward end; the latter wheels must be supported in the same manner as the wheels or rollers in the hinder end. The shaft in the forward end should be placed in the centre or back of the end of the machine, also an additional axis or round iron twenty inches long should go through about the centre of each head. The bolts which support the wheels or rollers in the hinder end may be fitted so as to turn, and may extend through on the outside of the machine, and the shaft may be connected with the wheels on the forward or hinder end of the machine by means of suitable gearing or by drums & bands or belts, either on the inside or outside of the machine. Also in each of the end pieces of the ten pieces of boards which go from one side of the machine to the other, may be placed two friction rollers of suitable dimensions, to facilitate the motion of the tread and near each end of the machine on the inside of the side planks are fixed circular guides for the rollers of such size and in such a manner as to regulate the motion of the treads when rising and falling. By a second method of making this machine the chain, rope, or belt, for the purpose of connecting the treads and turning the spur wheels, is not used. According to this method

Method the side planks being nine feet and a half long and nine inches and a quarter wide, extending across the machine nine and three eighths inches from end, as a bar of iron, three eighths of an inch square and let into the under side of the side planks three eighths of an inch. Two pieces of board four inches wide and one inch thick, extend the whole length of the machine and are made fast to the under edges of the side planks. Two pieces of board in the central part of the machine as a cap it four and five eighths inches from the top of the sides. Two shafts thirteen & three eighths inches from each end, rest in boxes in the sides of the machine and one of the shafts extends through on the outside of the machine a suitable distance for applying the power of the machine. On each of these shafts on the inside of the side planks and two inches therefrom, are four notched wheels seven and seven eighths inches in diameter, seven and seven eighths inches from the shafts and between each of them, and each end of the machine are two other notched wheels of the same dimensions, half an inch from the sides of the machine and running on bolts secured in the sides. Between the notched wheels and the side planks let into the sides are eight small gear wheels, three and a half inches in diameter and half an inch thick and between each pair of the small gear wheels also let into the sides is another gear wheel four and three eighths inches in diameter which runs on a round bolt secured in the side planks. The object of these gear wheels is to cause the outer notched wheels to move in the same direction as the inner ones. Four of the small gear wheels are fixed on the shafts and the other four are on the same bolts with the notched wheels. The treads are twenty four in number, ten inches long and four to a inch widthways of the machine. On each side of each tread are five iron bolts, half an inch in diameter and one and a half from each other, the ends being one inch from the

ends of the tread. The bolts are inserted in the treads so far as to render them sufficiently firm—the two end bolts are one and extend out two inches and three quarters, on the other end two inches and a quarter, the remaining six seven eighths of an inch. One of iron a quarter of an inch thick, and an iron and a quarter wide having holes made therin to correspond with the bolts, is placed on the bolts on each side of the treads. On the end bolt of each tread are four fiction rollers one inch and seven eighths in diameter and half an inch thick. On the crop pieces in the central part of the machine, and three inches from the side planks on each side of the machine, are two iron bars or pieces of board, seven feet long, two and a half inches wide and one inch thick and five eighths of an inch from each other and fastened upright to the crop pieces under them by screws or bolts. Twenty one fiction rollers, three inches in diameter and half an inch thick made of iron or wood are placed between these two iron bars or pieces of board on each side whose centers are four inches apart and whose ayes or arbors are inserted in the iron bars or boards. At each end of the machine seven eighths of an inch from the end, are circular guides consisting of a half circle at each end nine inches and a quarter in diameter, made of plank or iron, two inches thick and fastened to the side planks. Nine and a half inches from one end and on each of the side planks and three quarters of an inch from the top and bottom is a half circle guide, seven inches and seven eighths in diameter and half an inch thick. Eight inches and three quarters from the other end and one inch and seven eighths from the top and bottom, is another circular guide, consisting of the arc of a circle whose diameter nine inches and three quarters and the chord of the arc is five inches and three eighths, and the thickness of the guide is two inches. At one end of each tread and on the under side thereof and near to the edges of the treads are two pieces of wood or iron fastened with screws or bolts, three inches and five eighths long on the side joining the tread and one and a quarter and seven eighths deep at the end of the tread, the other

end of the pieces comes to an edge and the under side is an arc of a circle whose diameter is nine inches and a quarter. On each end of the treads are thin iron plates, to prevent the wear of the treads. Instead of the inside guides, the pieces of wood or iron on the under side of the treads and the bar of iron which is let into the under side of the side planks, may be used for the purpose of regulating the rising & falling of the treads two inches on each shaft, nine inches long, two and a half inches wide and half an inch thick, let on to the ends of the shafts half an inch from the side planks and secured by bolts or screws so as to move or swing thereon. Three inches and three quarters from the centre of the shafts, in both ends of these iron, are holes five eighths of an inch in diameter, to receive the ends of the bolts in the ends of the treads as they rise and fall. Three inches from the shafts towards the end of the machine are two circular pieces of iron three quarters of an inch thick in the centre and regularly diminishing in thickness so as to come to an edge at the extremities and made fast to the side planks. By means of these circular iron, the ends of the bolts on the treads are made to enter the iron on the shafts by which they are held while the treads pass round the notched wheels in ascending and descending. A third method of constructing this machine varying from those above described is as follows. The machine being nine feet long, twenty five inches wide and fourteen inches deep, five pieces of plank, four inches wide and two inches thick, placed at equal distances from each other, four inches and a half from the top of the side planks and inserted in them nine inches from each end of the machine, and in the middle of the side planks, is a shaft which runs in boxes set in the planks. The forward shaft is one inch and a quarter square, and the hinder shaft two inches square, and extends eight inches from the bearings for the purpose of applying strain or gearing. On each of these shafts are two wheels, which run near to the side of the planks on the inside, being two inches in diameter, and made without hubs.

two and three quarter inches distant from one another, and three quarters of an inch deep. There are seventy-four heads for the horse to step upon, each of which is supported and carried on arbors or shafts twenty two inches long and rounded two inches from the ends, and on each end is a friction roller two inches and a half in diameter and half an inch thick, running one inch and a half from the end. On the top of the shafts or arbors, is fastened with screws or bolts, a strip of board eighteen inches long, two inches and three quarters wide and one inch thick. On the top of every second one of these strips, are pieces of wood or iron three quarters of an inch square and five inches and a half long. These are fastened across each end of them to prevent the heads from canting. On the top of every other one of these strips, is a piece of plank sixteen inches and a half long, five inches and a half wide and two inches thick, setting the board and shaft or arbor equally on each side. The ends of the shafts or arbors, mesh into the notches in the low inch wheels above mentioned. The ends of arbors on the heads are kept in the notches or places made for them in the wheels, by means of a circular guide made to fit on the friction rollers of the heads, whilst moving round the notched wheels. The friction rollers on which the heads run, are kept in a direct course by strips of plank above and below the rollers. These strips are secured to the machine on the inside near the top and bottom with spikes, bolts or pins. The boxes and circular guides at the hinder end of the machine are connected together so as to be moved back and forth by means of keys in order to bring the heads suitably near each other. These heads may be made of cast iron cast whole with the exception of the friction rollers and the top plank or sheathing, and the pieces that crop on the ends of the heads may be cast on every head, instead of every other head. In constructing this machine according to either of the foregoing methods the dimensions may be increased or diminished in any degree that may be desirable. The machine may be put in motion by means of horses or other animals. In operating with this machine

A horse or other animal is introduced within the outside frame, made fast before and behind to the cross timbers at the top of the uprights. The horse or other animal is made to step or travel upon the treads, by which means the treads are caused to move towards the hinder part of the machine. When the machine is of the first, above described mode of construction, as the treads pass from the iron bars on which the rollers move, they descend successively to the two strips of boards which go the whole length of the machine and upon them by means of the chain, rope or belt, are caused to the forward end of the machine with the same side upwards and the same end towards the forward end of the machine. At the forward end of the machine the treads are successively raised by the aid of the chain upon wheels, rollers, and two pieces of iron and made to pass again upon the iron bars. As the treads move, the shaft is also put in motion. When the machine is of the second (described) mode the treads move, fall and rise in a similar manner by means of the various mechanical contrivances in that mode specified and the shafts are put in motion by the bolts of the treads, which in their progress mesh into the notched wheels. When it is of the third described mode the treads being placed closely together form a kind of belt or band, and the treads as they arrive at the hinder & forward ends, instead of falling and rising as in the former modes, turn or roll round as they pass over the notched wheels. In order to apply the power of this machine to the practical purpose of moving other machinery, the latter must be connected with the long shaft of the machine, by the use of steel gearing, as the nature of the case may require. By varying the dimensions of the machine it may be made applicable to the carrying of a great variety of operations. It may be used for propelling boats, to carry machinery for sawing wood, in gathering grain, and for going through with numerous other mechanical purposes.

What I claim as new in this machine, and the improvement for which I seek an exclusive privilege, is the arranging

and putting together as firsty and secondly, to make for the purpose of applying horse or other animal power in the way hereinbefore set forth, the various portions of the running parts of the machine and the method of arrangement therein specified, of these parts whereby the running parts are kept and maintained in their proper place and position, and also the principle of causing the treads to fall and rise at the ends of the machine without turning or rolling as stated therein - also in the method thirdly above described so much of the construction of the treads as consists in connecting the left overbord with the treads, also the principle of connecting and connecting these treads together without the aid of chains, belts or bands, by means of the guides and also the principle of casting the treads entire as herein stated - In witness whereof I have hereunto set my hand and seal at said Cottenham the 27th day of April
A.D. 1834.
